FINE SPINNING FRAME

Etsuro Kato, Meguro-ku, Tokyo-shi, Japan

Application August 19, 1936, Serial No. 96,884
In Japan October 25, 1935

1 Claim. (Cl. 118—15)

This invention relates to certain improvements in fine spinning frame of the type in which a sliver moves vertically in the direction of the axis of a spindle disposed in a vertical position.

5 One object of the invention is to provide a simple and compact spinning frame.

Another object of the invention is to make the variation of tension of winding yarn due to ballooning independent of the elapsed time after the 10 doffing of cop.

In the accompanying drawing:

Fig. 1 is a side view of a fine spinning frame embodying the invention.

15 Fig. 2 is a front view of the spinning frame partly broken away.

Fig. 3 is a diagram of operating characteristic curve illustrating the relation of revolving speed of spindle and elapsed time after doffing of cop in fine spinning frame embodying the invention.

20 Referring to Figs. 1 and 2, 1 represents a gear case, 4 a poker arm which is movably mounted on a shaft 7. One end of said poker arm is operatively connected with a cam (not shown) in the gear case 1 by means of a connecting link 2. A lever 5 is securely or integrally connected with the poker arm 4 so as to be rocked when the poker arm 4 is rocked. Another poker arm 4' is arranged to be moved at the same period as that of the motion of the poker arm 4 by the rocking arm 5 through means of a connecting link 6 and a lever 5'. The poker arm 4 and a number of the other poker arms 4' are arranged in a line nearly below the center line of the machine frame 10 supporting the driving electric motors 9 individual to the spindles 8. Each of the poker arms 4 and 4' is provided on its free end with a roller 13 adapted to engage with the lower end of a vertical rod 14 which extends through the beams of the machine frame 10. The vertical rod 14 is guided by the roller stand 17 and a lower tie beam 18 of the machine frame 10, through which said rod extends. To the vertical rods 14 are secured the beams 15 for carrying ring rails 12, 12' and another beam 16 for carrying guide rails 11, 11', and consequently said vertical rods and these ring rails and guide rails will be moved as one unit when the poker arms 4 and 4' are moved.

45 From the foregoing, it will be seen that the arrangements are considerably simplified. Further, it is apparent that the guide rail 11 and the ring rail 12 are moved with a fixed distance between them, any relative motion not being made, and that the sliver is moved vertically in the direction of the axis of the spindle disposed 50 in vertical position, and consequently yarn will be

drafted in a vertical direction in the sliver and guide, so that a constant tension of yarn may be ensured irrespective of the motion of the guide moved with the ring rail. The fact that there is no relative motion between the guide rail 11 and ring rail 12 upon their movement will result that variation of the tension of yarn due to ballooning is independent of the elapsed time after doffing of the cop.

55 In fine spinning frames heretofore in use, the guide and spindle are positioned in a fixed relation, and the cop building is effected by up-and-down motion of the ring rail, and accordingly in the beginning of the cop building and distance between the guide and traveller is larger and the ballooning will increase, whereby yarn will be caused to more frequently be broken, as yarn is more frequently caused to foul the separator and other parts due to increase in the tension of the yarn. In order to avoid this disadvantage, the revolving speed of the spindle must be lowered. On the contrary, toward the end of the cop building the distance between the guide and traveller is smaller and the size of the balloon will decrease, so that yarn is likely to be broken by a small shock, and accordingly the revolving speed must also be lowered to avoid the said disadvantage. With fine spinning frames heretofore in use, therefore the number of revolutions per minute of the spindle should be related to the elapsed time after 20 the doffing of the cop so that the control of operation of the spindles becomes more troublesome and the arrangement becomes more complicated. With the fine spinning frame embodying the invention, the guide and ring rail are related so 25 as to be moved keeping a fixed distance between them, whereby the disadvantage of lowering revolving speed of spindle as mentioned above will be avoided, and the variation of tension of yarn due to ballooning is regular from the beginning 30 to the end of winding of cop and independent of elapsed time after the doffing of cop as illustrated by a diagram in Fig. 3.

35 As seen from the foregoing description, with the arrangement according to the invention, the drafting tension of yarn is constant irrespective of up-and-down motion of the guide moving with the ring rail, as the direction of drafting yarn in sliver and guide is vertical due to sliver being moved vertically in the direction of the axis of 40 spindle disposed in vertical position, and the control of the operation of the spindle is facilitated, as the ring rail and guide rail are moved in a fixed relation keeping a fixed distance between them to make uniform the tension of the yarn 45 50 55

- due to ballooning and to give the spindle an operation control characteristic as illustrated in Fig. 3, independently of the elapsed time after doffing of cop. Further, the arrangement for transmitting up-and-down motion of the ring rail and guide rail is extremely simplified, as the ring rail and guide rail are securely mounted on the vertical rod which is moved up and down for cop building. Still further the size of the spinning frame may be made smaller, as the space between two sides of the machine frame may be decreased due to the vertical rod being disposed in an intermediate position between the spindles arranged on two sides of the machine frame, and a smooth operation of the vertical rod may be ensured due to the guiding function provided by the tie beam forming part of the machine frame through which the vertical rod extends.

Having now particularly described and ascer-

tained the nature of my said invention and in what manner the same is to be performed, I claim:

A fine spinning frame comprising, in combination, a frame, two parallel rows of vertical spindles arranged on opposite sides of the frame, two parallel rows of drafting apparatus arranged on opposite sides of the frame and comprising parallel rows of vertically arranged drafting rollers to draft slivers vertically in substantial coaxial relation to said spindles, vertically slideable rods mounted in the frame and disposed intermediate the rows of spindles, ring rails and guide rails secured in spaced apart relation on said vertical rods, actuating means operably connected to said rods for simultaneously moving said rods vertically, and individual motor driving means for each of the spindles.

ETSURO KATO.
